UNITED STATES PATENT OFFICE.

EDWARD RENNERT, OF BALTIMORE, MARYLAND, ASSIGNOR OF ONE-HALF TO GUY E. TIMMINS, OF BALTIMORE, MARYLAND.

INDICATOR FOR LOCKS.

1,161,158.

Specification of Letters Patent. Patented Nov. 23, 1915.

Application filed July 6, 1912. Serial No. 708,013.

To all whom it may concern:

Be it known that I, EDWARD RENNERT, a citizen of the United States, residing at Baltimore city, State of Maryland, have invented 5 certain new and useful Improvements in Indicators for Locks, of which the following is a specification.

This invention relates to an indicating mechanism for locks and especially locks 10 for doors of hotel rooms, apartment houses, steamer state rooms and all doors where it is desirable to indicate whether the door is locked or not.

The invention has for one of its objects 15 to provide means for readily indicating on the outer side of the door whether the door is unlocked, locked from within or locked from without.

Another object is to provide an indicator 20 which is positive in its operation, the indicating means being rigidly attached to the bolt and consequently moving therewith.

Another object is to provide a lock, the condition of which may be ascertained 25 either in the dark or when the lock is visible.

Other objects and novel features of the invention will be apparent from the following description in connection with the accompanying drawings, in which,

Figure 1 is a perspective view of a portion of a door and its lock looking from the outside, the lock embodying my invention. One of the bolts is shown as in locked position 35 and so indicated, while the other bolt is shown as in unlocked position and so indicated. Fig. 2 is a perspective view of the outside of the lock removed from the door, one of the bolts being shown in unlocked 40 position and the other shown in locked position. Fig. 3 is a plan view of the lock showing the cover of the casing removed and the parts therein in the position assumed when the door is unlocked. Fig. 4 is a plan view similar to Fig. 3, parts being broken away showing the bolt operable 45 from the outside in retracted position and the bolt operable from within being shot into locking position, the tumbler for locking the latter removed to more clearly illustrate the operation. Fig. 5 is a perspective view of one of the bolts and its separable indicating member.

Referring to the drawings, the numeral 10 designates the locking door to which the 55 front plate 11 is applied by means of the screws 12 as is usual. Connected to the front plate 11 and extending rearwardly therefrom to be set into a recess mortise in the door is a casing member 13 which is 60 provided with the removable cover 14. The cover is set on the front side of the casing and has a key hole 15 therein, accessible from the outside only. The cover 14 is also provided with an opening 17' for the spindle 17, and in line with the spindle opening 17' and hole 15 there are two rectangular openings 141 and 142 through which project the indicating devices to be hereinafter explained. The casing 13 is provided with 70 a key hole 16 accessible through the door from the inside. A knob spindle 17 having knobs 18 is arranged to operate the latch 26 in a manner well understood.

Two independent and parallel bolts 28 75 and 29 operate within the casing 13. In the present case the bolt 28 constitutes the locking means operable from within, while the bolt 29 is only operable from without. However, this arrangement may be changed 80 or varied to suit the conditions.

As illustrated in Fig. 5 the bolt 28 comprises an enlarged end section 30 cast integral with the thin rear section 31. The end section 30 passes through the front face 85 plate 11 and engages in the plate on the door casing. The rear section 31 has two narrow openings 32 and 33 extending therethrough and a cut away section 34 to receive the key, and a recess 35 in its under side, the function of which will presently be explained. Rising from the outer face of the section 31 and near the cut away portion 34 there is an upstanding lug 36 which is cast integral 90 with the rear section 31 and has a threaded opening 37 in its upper end to receive the threaded shank 38 of a flat rectangular plate or disk 39. The construction of the bolt 29 is substantially the same as the bolt 28 with the exception that there is no recess in its 100 under side corresponding to the recess 35. The openings 32 and 33 in the narrow section 31 of the bolts fit over and are guided by lugs 40-40' and 41-41' integral with the casing 13. The lug 41' is not shown in 105 the figure but corresponds to the lug 41

shown in Fig. 4. The lugs 40, 41 and 41' constitute stops and guides for the bolts 28 and 29 respectively. The lugs 40, 40' are circular in cross section and have pivotally mounted thereon key operated tumblers to releasably hold the bolts 28 and 29 in their respective positions. The tumbler 42 for the bolt 28 has an opening therein which has an inwardly projecting lug 44 intermediate the ends of the opening 43 to cooperate with the upstanding lug 36 on the bolt, locking the bolt in either position. The tumbler is releasably held against movement by the spring 45 which is fastened to the tumbler at one end and the other end bears against a lug 46 integral with the casing. The tumbler 42 may be operated by a key introduced through the key hole 16 from the inner side of the door, thereby raising the stop or projection 44 out of the way of the lug 36 so that the bolt 28 may be shot forward when the bit of the key engages the end of the bolt adjacent the key hole. The lug 40' has pivoted thereon a plurality of tumblers 47, 471, 472 and 473. The tumblers each have an opening 48 at their free ends through which the lug 36' on the bolt 29 projects. The openings are formed with projections 49 similar to the projections 44 on the tumbler 42 and each of the tumblers is releasably held by a separate spring 50, the inner end of which is rigidly connected to the tumbler and the outer end to a lug 46' integral with the casing 13. The bottom tumbler has an upstanding projection 51 thereon to limit the movement of the same. The tumblers 47, 471, 472 and 473 may be actuated from the outside by a suitable key projected through the key hole 15. The outer side of the door 10 has an escutcheon plate 52 fitted thereon which has openings therein to receive the knob spindle 17 and a key opening 53 in line with the key hole 15 in the cover 14. Between the opening for the knob spindle and the key hole 53 there are two circular openings 54 and 55 substantially in line with the upstanding lugs 36 and 36' on the bolts 28 and 29. The plates 39, 39' on the upstanding lugs 36 and 36' reciprocate across the openings 54 and 55 and cover and uncover the same when the bolts 28 and 29 are shot from one position to the other. For example, when the bolt 28 is shot forward into locked position the lug will have been turned from the inside and the plate 36 moving therewith will uncover the opening 54 indicating that the door is locked from within. Again, when the bolt 29 is shot forward into locked position the hole 55 will be uncovered and indicate that the door has been locked from the outside. If both openings 54 and 55 are covered, it will be obvious that the door is unlocked. It will thus be possible to ascertain at a glance the exact condition of the

lock, and there will be no necessity of the chamber-maid or any one else desiring to work in or enter the room to rattle the door or cause any disturbance. In case the hallway or corridor is dark, the condition of the openings 54 and 55 may be ascertained by simply inserting the end of the key or other small instrument similar to a nail into the openings. By the sense of touch the one trying the lock will thus be informed of the condition of the same.

The double armed lever pivoted on the pivot 56 integral with the casing 13 and locked between the bolts 28 and 29 has an arm 57 which lies flush with the bottom of the casing and extends into the recess 35 on the lower side of the bolt 28. On the opposite side of the pivot 56 and connected with the arm 57 there is an arm 58 having an upstanding end 59. The outer face of the end 59 engages against the tumblers 47, 471, 472 and 473 when the bolt 28 is shot into locked position from the inside as indicated in Fig. 4, thus preventing any one on the outside from operating the bolt 29 to lock the door from the outside when the door is locked from within.

In assembling the lock, the plates 39 and 39' are removed from the main lock and the latter is set in position in the recess in the edge of the door. The lugs 36 and 36' project through the openings 141 and 142 in the cover 14 and when the lock is set in the recess in the door the lugs 36 and 36' will project into an opening 60 communicating with the recess in the door and the plates 39, 39' may be adjusted on the lugs 36 and 36'. The plates 39, 39' slide along the inner surface of the escutcheon plate 52 and may be adjusted inwardly or outwardly as desired.

The operation of the lock and indicating mechanism will be clear from the foregoing description. The indicators show whether the door has been locked from the inside or from the outside and will also indicate when the door is open or unlocked. Each bolt is independent of the other, except that the bolt on the inside cannot be opened from the outside, nor can the bolt on the outside be opened from the inside, nor operated when the inside bolt is shot to locked position. The simple arrangement of the indicating mechanism and the action of the same without the assistance of springs, levers or extra attachments to the key or lock affords a device which is adapted to be mounted on most makes of locks whether for single or double indication. By using a double lock the door is made burglar proof, there being no key hole on the outside of the door to connect with the inside bolt.

As numerous changes may be made in the construction of the mechanism without departing from the spirit of the invention, it is not intended that the invention shall be

limited to the exact details as shown and described.

Having described my invention what I claim and desire to secure by Letters Patent is:

1. In a lock, the combination of a bolt having a lug thereon, locking mechanism capable of coöperating with said lug to retain the bolt in one of two positions, and indicating means connected to the lug on said bolt.

2. In a lock, the combination of a bolt having a lug thereon, locking mechanism capable of coöperating with said lug to retain the bolt in one of two positions, and an indicating device rigidly mounted on said lug whereby said device moves with the bolt.

3. In a lock, the combination of a casing adapted to be fitted on a door, locking mechanism in the casing comprising a plurality of bolts, a member having openings therein, and means controlled by the bolts capable of covering and uncovering the openings in said member to indicate the position of each of the bolts.

4. In a lock, the combination with a member having an opening therein, of a bolt having a lug thereon, locking mechanism capable of coöperating with said lug to retain the bolt in locking position, and a part at the outer end of said lug movable into and out of registry with said opening whereby said part on said lug will cover and uncover said opening so as to indicate

the position of said bolt by sight or by the sense of touch.

5. In a lock, the combination of two bolts, one of which is operable only from one side of the door and the other being operable only from the opposite side of the door, and means including an apertured plate on the outer side of the door for indicating the positions of the two bolts.

6. In a mortise lock, the combination of a casing having an opening in a side wall thereof, a bolt and locking mechanism therefor within said casing, said bolt having a part which coöperates with said locking mechanism, and a plate having an opening therein, said part of the bolt extending through the opening in the side wall of the casing and movable with respect to said opening in said plate and coöperating therewith to indicate the position of the bolt.

7. In a lock, the combination of a casing, a locking bolt in said casing, locking mechanism in said casing for retaining said bolt in locking position, and an indicating device extending outside of said casing and rigidly mounted on said bolt whereby said device is carried by and moves with said bolt.

In testimony whereof I affix my signature in presence of two witnesses.

EDWARD RENNERT.
